UNITED STATES PATENT OFFICE.

HOWARD M. BARBER, OF STONINGTON, CONNECTICUT, ASSIGNOR, BY MESNE ASSIGNMENTS, TO C. B. COTTRELL & SONS COMPANY, OF NEW YORK, N. Y., A CORPORATION OF DELAWARE.

TYMPAN FOR BOX CUTTING AND SCORING MACHINES.

1,158,772.

Specification of Letters Patent.

Patented Nov. 2, 1915.

Application filed February 3, 1911. Serial No. 606,384.

To all whom it may concern:

Be it known that I, HOWARD M. BARBER, a citizen of the United States, and resident of Stonington, in the county of New London 5 and State of Connecticut, have invented a new and useful Improvement in Tympons for Box Cutting and Scoring Machines, of which the following is a specification.

This invention relates to improvements 10 in tympons for box cutting and scoring machines and has particularly for its object to provide a novel device for attaching the steel cutting jacket or tympan to the cylinder of a bed and cylinder machine.

15 A further object is to provide certain improvements in the construction, form and arrangement of the several parts whereby the tympan may be readily and quickly removed from its engagement with the surface 20 of the cylinder for permitting the application of the make-ready to the surface of the cylinder, means being employed for drawing the tympan snugly down into position 25 on the cylinder.

30 25 A practical embodiment of my invention is represented in the accompanying drawings, in which—

Figure 1 represents in side elevation the impression cylinder of a bed and cylinder 35 box cutting and scoring machine with the invention applied thereto, a portion of the jacket being broken away at its hinged end to more clearly illustrate the parts beneath the same, Fig. 2 is a transverse section taken

40 in the plane of the line A—A of Fig. 1, Fig. 3 is an enlarged detail section showing the position of the parts at the hinged end of the tympan in the position which they assume when the tympan is in engagement

45 with the surface of the cylinder, Fig. 4 is a similar view showing the parts in the position which they assume when the tympan has been swung out of the way for obtaining access to the surface of the cylinder, and Fig. 5 is an enlarged detail section showing the parts at the free end of the tympan which is to be removably and fixedly secured to the cylinder.

50 The cylinder is denoted by 1 and its impression surface by 2. The usual grippers are denoted by 3. The cylinder is cut away at both ends of the impression surface 2 as shown at 4 and 5. The tympan is denoted by 6, which tympan may be a steel cutting

jacket when the device is used in connection 55 with box cutting and scoring machines. One end of the tympan 6 projects beyond one edge of the impression surface 2 and is fixedly secured to a rock bar 7 mounted in the outer free ends of a plurality of arms 8, 60 the inner ends of which arms are pivotally mounted on a bar 9 extending lengthwise of the cylinder 1 within the same. The free end of the tympan 6 is removably attached to the impression surface 2 of the cylinder 65 adjacent to the grippers 3. In the present instance, the means for attaching the tympan comprises a longitudinal series of screw bolts 10 and their tightening nuts 11, the bolts 10 passing freely through the walls 70 of the cylinder 1 and being prevented from turning as, for instance, by projections 12.

The means for drawing the tympan tightly against the impression surface of the cylinder comprises a longitudinal series of 75 adjusting screws 13 passing through the rock bar 7 with their inner ends in engagement with the adjacent edge of the impression surface 2. These adjusting screws 13 may be provided with lock nuts 14. 80

Straps 15 are provided for limiting the swinging movement of the bars 8, each of which straps is secured to one of the cylinder arms by a bolt 16 and has a pin and slot connection 17, 18, with its arm 8. It is desirable that two of these straps 15 be used, one at each end of the cylinder. 85

Means are provided for limiting the swinging movement of the rock bar 7, which means, in the present instance, is shown as a plate 19 secured to the arm 8 in the proper position to engage the bar 7 when the tympan is swung to the limit of its outward movement away from the impression surface of the cylinder. 95

The relation between the hinge bar 7 and the arms 8 is such that the outer face of the hinge bar to which the tympan 6 is attached will be in alinement with the impression surface 2 of the cylinder so that the proper 100 tightening effect may be exerted upon the tympan when its free end is secured to the cylinder.

In operation, supposing the tympan to be swung into its open position, as indicated in Fig. 4, the make-ready 20 may be pasted onto the impression surface of the cylinder. The tympan may then be swung down into

position over the impression surface and its free edge fixedly secured in position by the bolts and nuts 10, 11. After the free end of the tympan has been secured in position, the 5 adjusting screws 13 at the hinged end of the tympan are turned to draw the tympan snugly down against the impression surface.

To remove the tympan from its engagement with the impression surface of the cylinder, the adjusting screws 13 are first turned 10 to loosen the strain on the tympan and the clamping screws 10. The nuts 11 may then be unscrewed from the clamping screws 10 and the clamping screws removed. The tympan 15 is then shifted along the cylinder as far as the links 15 will permit. The tympan may then be swung back away from the cylinder to give ready access to the impression surface 2.

20 While I have described this invention in connection with a box cutting and scoring machine, I do not wish to limit myself to the use of the tympan in such a connection only but contemplate its use in connection with 25 impression cylinders wherever it can be used.

What I claim is:—

1. The combination with an impression cylinder, of a tympan having one end removably fixed to the cylinder, a circumferentially movable rock bar secured to the other end of the tympan, having its outer face in alinement with the impression surface of the cylinder and a swinging support for the rock bar.

35 2. The combination with an impression cylinder, of a tympan having one end removably fixed to the cylinder, a circumferentially movable rock bar secured to the other end of the tympan having its outer face in 40 alinement with the impression surface of the cylinder, means carried by the rock bar in position to engage the cylinder for adjusting the circumferential position of the rock

bar and a swinging support for the rock bar.

3. The combination with an impression cylinder, of a tympan having one end removably fixed to the cylinder, a circumferentially movable rock bar secured to the other end of the tympan, having its outer face in 50 alinement with the impression surface of the cylinder and arms hinged within the cylinder forming a swinging support for the rock bar.

4. The combination with an impression cylinder, of a tympan having one end removably fixed to the cylinder, a circumferentially movable rock bar secured to the other end of the tympan, having its outer face in 55 alinement with the impression surface of the cylinder, arms hinged within the cylinder forming a swinging support for the rock bar and means carried by the rock bar in position to engage the cylinder for adjusting the circumferential position of the rock bar.

5. The combination with an impression cylinder, of a tympan having one end removably fixed to the cylinder, a circumferentially movable rock bar secured to the other end of the tympan, having its outer face in 70 alinement with the impression surface of the cylinder, arms hinged within the cylinder forming a swinging support for the rock bar, means carried by the rock bar in position to engage the cylinder for adjusting 75 the circumferential position of the rock bar, and means for limiting the circumferential movement of the rock bar.

In testimony, that I claim the foregoing as my invention, I have signed my name in 80 presence of two witnesses, this first day of February A. D. 1911.

HOWARD M. BARBER.
